CLAIM

The ornamental design for a horseshoe game, as shown and described.

DESCRIPTION

FIG. 1 is a top right side perspective view of a horseshoe game, showing my new design;

FIG. 2 is a right side elevation view thereof, with the left side elevation view being identical;

FIG. 3 is a front side elevation view thereof, with the rear side elevation view being identical;

FIG. 4 is a top plan view thereof; and,

FIG. 5 is a bottom plan view thereof.
